UNITED STATES PATENT OFFICE

118,492

DESIGN FOR A CANDLE LAMP

Norbert J. Baumer, Baltimore, Md., assignor to
A. Gross Candle Co., Inc., Baltimore, Md., a corporation of Delaware

Application November 14, 1939, Serial No. 88,281

Term of patent 14 years

To all whom it may concern:

Be it known, that I, Norbert J. Baumer, a citizen of the United States, residing at Baltimore, State of Maryland, have invented a new, original, and ornamental Design for a Candle Lamp, of which the following is a specification, reference being had to the accompanying drawing, forming a part thereof, and in which:

Fig. 1 is a perspective view of a candle lamp showing my new design.

Fig. 2 is a top plan view of the same.

The essential features of the design reside in the parts shown in solid lines.

I claim:

The ornamental design for a candle lamp, substantially as shown and described.

NORBERT J. BAUMER.
